INVENTOR.

Maurice R. Kohn

BY

Ralph Koenig

ATTORNEY.

UNITED STATES PATENT OFFICE.

MAURICE R. KOHN, OF ST. LOUIS, MISSOURI, ASSIGNOR TO CHARLES A. CHAMPLIN, OF HOPE, ARKANSAS.

VALVE.

1,277,606.

Specification of Letters Patent.

Patented Sept. 3, 1918.

Application filed November 19, 1917. Serial No. 202,769.

To all whom it may concern:

Be it known that I, MAURICE R. KOHN, a citizen of the United States, residing at the city of St. Louis, State of Missouri, have invented a certain new and useful Improvement in Valves, of which the following is a specification, reference being had to the accompanying drawing, forming a part thereof.

10 This invention relates to a certain new and useful improvement in valves, the principal object of my present invention being to provide a simple and efficient and readily accessible valve having a small number of parts and comprising a valve-member adapted to be automatically held to its seat in valve-sealing or closing position under the outward pressure or influence of the compressed air or other fluid within the containing vessel or receptacle and to be unseated under the inward pressure or influence of the fluid when the said vessel or other receptacle is being filled or inflated.

15 With the above and other objects in view, my present invention resides in certain novel features of form, construction, arrangement, and combination of parts, all as will herein-after be described and afterward pointed out in the claim.

20 My present valve is especially useful in connection with the inner tubes of automobile tires and the like adapted to be inflated by and to contain compressed air and will be here so described; but it is to be understood that my new valve may equally well be employed in connection with other vessels or receptacles and with other fluids.

In the accompanying drawing,

25 Fig. 1 is a vertical sectional view of a valve embodying my present invention in preferred form;

30 Fig. 2 is a plan view of the apertured disk forming part of the valve and which is adapted to provide a support or rest for the valve-closing member during the inflation or filling of the tire-casing or other vessel;

35 Fig. 3 is a cross-sectional view through the valve on approximately the line 3—3, Fig. 1;

40 Fig. 4 is a vertical sectional view through a slightly modified form of valve embodying my invention;

45 Fig. 5 is a detail view, partly in section,

of the valve-member proper of the valve shown in Fig. 4; and

Fig. 6 is a vertical sectional view through another modified form of valve embodying my invention.

Referring now more in detail to the said drawing, in which like reference characters refer to like parts throughout the several views, 1 indicates a short tubular member which is of suitable diameter and which forms the valve-casing. This member or 55 casing 1 is preferably externally threaded, as shown, and is adapted to be suitably fixed or mounted at its lower end upon, and to communicate with the chamber of, the tire-tube or other vessel 2 to be filled or inflated. 60 At its upper end, casing 1 is counter-bored, as at 3, to provide an internal annular shoulder, as at 4. Supported by the shoulder within casing 1, is an apertured disk 5. The counter-bored portion 3 of casing 1 is internally threaded to receive an externally threaded hollow nozzle or outlet member 6 having a straight lower portion of substantially the depth of the counterbore in the casing and an annularly contracted or substantially cone-shaped mouth-portion 7. 65 The lower or inner end of the nozzle member is adapted to engage directly the disk 5 to thereby securely hold the disk in place upon its seat or shoulder 4. Loosely disposed within nozzle-member 6 is a sphere 8 of any suitable material and of such size or diameter relatively to the mouth-portion 7 of the nozzle-member 6 as to normally, under the outward pressure or influence of 70 the compressed air or other elastic fluid or the like within the tire-tube or vessel 2, automatically seat in said contracted portion 7 and thereby obstruct and close the mouth thereof.

75 In use or operation, the sphere 8 will, as stated, be firmly held to its seat in valve-closing position under the constant outward pressure of the compressed air or other fluid within the tube or other vessel 2. Should the tube or other vessel 2 become punctured or otherwise deflated, the sphere 8 will be supported and prevented from falling into the tube or vessel 2 by said apertured retaining disk 5, which disk 5 will similarly support the sphere 8 during the inflation or filling of the tube or vessel 2. On filling or inflating the tube or vessel 2, should

the sphere 8 be held to its seat by the outward pressure of the air or other fluid within the tube or vessel, then the greater pressure of the incoming air or other fluid will unseat the sphere 8, so that the incoming air or other fluid may readily flow into the tube or other vessel 2.

I have found my new valve to be exceedingly efficient in use; it is most simple and 10 inexpensive in its construction and permits ready disassembling of the parts for cleaning, etc., and permits of considerable wearing of the parts without requiring replacement or repair. Normally an internally 15 threaded protecting-cap 9 is threaded upon the casing 1, as shown.

The modified form of my valve shown in Fig. 4 is substantially the same as the preferred form of valve shown in Fig. 1, except 20 that the valve-member proper in this form of valve is in the form of a cylindrical block 10 of suitable material annularly beveled or cone-shaped at its upper end, as at 11, to operatively engage the inner wall of the 25 mouth-portion 7 of the nozzle-member 6 when in valve-closing position. The block or member 10 is further recessed on its under face, as at 12, to receive the upper end of a short pin or stem 13 fixed at its lower 30 end in the apertured disk 5^a, upon which pin or stem 13 the block or member 10 is slidable into and out of valve-closing position.

The modified form of valve shown in Fig. 35 6 differs from the preferred form of valve shown in Fig. 1, in that the internally threaded counter-bored portion 3^b of casing 1^b is somewhat extended to receive a plurality of nozzle and valve-members proper, 40 as shown. Fitting within casing 1^b and resting upon the shoulder at the lower end of counter-bored portion 3^b, is a similar apertured disk 5. Threaded within said counter-bored portion 3^b to engage upon 45 the upper face of disk 5, is a nozzle-member 14 formed internally with a beveled enlargement 15 to provide the member 14 with a contracted mouth substantially similar to the contracted mouth of nozzle-member 6. 50 Loosely disposed within the member 14 to

seat in its said contracted mouth to close the valve, is a sphere 8. Fitting within said counter-bored portion 3^b above said member 14, is an additional disk 5 and nozzle-member 6 with its sphere 8, substantially 55 similar in all respects to the disk 5 and nozzle-member and sphere 8 of the preferred form of valve shown in Fig. 1. In this form of valve, the upper sphere 8 normally 60 performs no function, the lower sphere 8 opening and closing the valve as before described in connection with the form of valve shown in Fig. 1. Should, however, the lower sphere 8 fail to perform 65 its function, then the upper sphere 8 will come into play to properly open or close the valve.

I am aware that minor changes in the form, construction, arrangement, and combination of the several parts of my new 70 valve may be made and substituted for those herein shown and described without departing from the nature or principle of my invention.

Having thus described my invention, what 75 I claim and desire to secure by Letters Patent is:

A valve, comprising a tubular casing, said casing at one end being counterbored and provided with internal screw-threads its entire depth terminating in a shoulder, an apertured disk seated within the casing upon said shoulder, a tubular nozzle member having a contracted, cone-shaped mouth portion at its outer end and an externally 80 screwthreaded straight portion at its lower end of substantially the same depth as the counterbore in said casing and adapted to be screwed into the threaded counterbored end of the casing and its inner end adapted 85 to directly engage said disk to hold it in place upon said shoulder, and a valve proper loosely disposed in the nozzle member and adapted to close the valve under outward pressure, the said disk serving as a support 90 for the valve proper when in open position. 95

In testimony whereof, I have signed my name to this specification.

MAURICE R. KOHN.
